UNITED STATES PATENT OFFICE.

JOHN C. BUCKBEE, OF CHICAGO, ILLINOIS.

SHAKING SCREEN.

Application filed January 2, 1920. Serial No. 348,748.

To all whom it may concern:

Be it known that I, JOHN C. BUCKBEE, a citizen of the United States, residing at Chicago, in the county of Cook and State of Illinois, have invented a certain new and useful Shaking Screen, of which the following is a specification.

The main and primary object of the present invention is to provide a novel form of shaking screen wherein a plurality of shaker beds are arranged in superimposed relation and in which are embodied efficient means for absorbing the jar and shock incidental to the operation of the shaker beds. This relieves the supporting framework of the jarring which arises in connection with the working of the screen, and prevents transmission of the same to the building structure in which the screen may be erected.

Other objects and advantages will appear as the nature of the invention is better understood, the latter consisting substantially in the novel construction, combination and arrangement of parts hereinafter fully described, illustrated in the accompanying drawings, and finally pointed out in the appended claims.

The invention is susceptible of embodiment in various forms, one of which is disclosed herein as indicative of the practical application of the invention, but this disclosure is to be considered only in an illustrative and not a restrictive sense.

In the drawings—

Fig. 1 is a plan view of a shaking screen constructed in accordance with the present invention, the screen fabric being omitted.

Fig. 2 is a longitudinal section thereof on the line 2—2, Fig. 1.

Fig. 3 is a detail elevation of one of the shock-absorbing devices associated with the screen.

Fig. 4 is a transverse sectional view on the line 4—4, Fig. 2.

Referring in detail to the accompanying drawings, the numeral 10 designates the supporting framework of the herein described screen. Arranged adjacent to one end thereof is a pair of oppositely-disposed journal boxes 11 in which a driving shaft 12 is mounted for rotation, power being applied to said shaft 12 by a driving pulley 13, or other suitable approved means.

Mounted on the shaft 12, adjacent to each end thereof, is a pair of eccentrics 14, the eccentrics of each pair being arranged at an

angle of 180° with respect to each other, each of said eccentrics being surrounded by a strap 15 of approved construction and to which is attached a connecting rod 16 which extends in a rearward direction from the shaft 12.

Suitably spaced apart, and extending transversely of the framework 10, is a pair of rock shafts 17, the ends of said shafts being journaled in bearings 18 mounted on the side members of the framework 10, and said rock shafts 17 sustain a pair of shaking screens 19 which are arranged in superimposed relation with respect to each other. These screens may be of any approved construction, including a shaker bed 20 with suitable screen fabric or cloth (not shown) applied thereto, and each of said beds is provided at its under side with a series of perforated blocks 21 for receiving a plurality of supporting shafts 22 by means of which the shaker beds 20 are supported in relation to the rock shafts 17. The rear ends of the shaker beds 20 are connected to the rear rock shaft 17 by means of a series of rocker arms 23 located in pairs at opposite sides of the shaker beds, each of which arms includes a perforated hub 24 arranged at one of its ends and a perforated head 25 located at the other end. The hubs 24 receive the rock shaft 17, the arms 23 of the upper bed 20 extending from said shaft 17 in an upward direction and having their heads 25 connected to the rear shaft 22 of that bed. The arms 23 of the lower bed 20 project downwardly from said shaft 17 and their heads 25 are connected to the rear shaft 22 of the lower bed. The arms 23 of the upper bed 20 are held in fixed relation to the shaft 17, as by means of set screws 26 arranged in the hubs of the upper rocker arms and impinging against the shaft 17. The rocker arms 23 of the lower bed 20, however, are free to move with respect to said shaft, the purpose of which will presently appear.

Associated with the forward rock shaft 17 is a series of rocker arms 27, each of said arms including a perforated hub 28 at one end and a perforated head 29 at the other. These rocker arms 27 are located in pairs at opposite sides of the shaker beds, the arms of each pair being arranged in reverse relation, similar to the reverse arrangement of the rocker arms 23. Certain of the arms 27 thereby extend upwardly from the shaft 17, and others depend therefrom. The per-

forated heads 29 of the arms 27 receive the ends of the forward supporting shafts 22 for connecting the arms with the forward ends of the shaker beds 20. The hubs 28 of the 5 upper arms are fixedly connected to the forward shaft 17, as by set screws 28'; while the corresponding hubs of the lower arms 27 are loosely mounted on said shaft 17 and, therefore, free to move with respect thereto, 10 and each of said arms is provided adjacent to the hub 28 thereof with an angularly-disposed horizontal perforated ear 30. By the reverse arrangement of the arms 27 of each pair, the perforated ears 30 thereof extend 15 across each other so that the perforations of the ears are vertically aligned. A tension bolt 31 passes through the aligned perforations of these ears, the head of the bolt projecting below the ear 30 of the lower arm 27, 20 while the threaded end of the bolt extends above the ear 30 of the upper arm. A flanged washer 32 is carried by each bolt 31 adjacent to its head, and interposed between said washer 32 and the perforated ear 25 30 of the lower arm 27 is a coil spring 33. The lower end of the coil spring is seated within the flanged washer 32, and its upper end likewise rests within a flanged seat 34 formed in the perforated ear 30 against 30 which the spring contacts. A pair of securing nuts 35 is arranged on the threaded end of each bolt 31, and said bolts serve to provide the required degree of compression for the springs 33 and likewise to hold the perforated ears 30 of each pair of arms 27 in 35 yielding relation to each other.

In the operation of the herein-described screen rotation of the shaft 12, through the oppositely-disposed eccentrics 14, will 40 impart reciprocating motion to the shaker beds 20 in opposite directions. By reason of the upwardly-extending rocker arms 23 and 27 being fixedly connected to the rock shafts 17, said shafts are actuated with the movement 45 of the upper shaker bed 20, the arms 23 and 27 of the lower shaker bed having free movement on said shafts 17. Due to the employment of the springs 33 and their connections with the several pairs of opposed rocker 50 arms 27, said springs will yield in the shaking movement of the screens, thus compensating for any variations in such movement, and serving to absorb the shock and jar incident to the reciprocation of the shaker beds 55 and the other operative parts of the mechanism. This, therefore, prevents lost motion in the mechanism, and the balanced disposition of all parts results in the confining of all movement within the machine. Each 60 screen is capable of independent movement with respect to the other within the control of the shock absorbing mechanism constituted by the springs 33 and their connections with the several pairs of opposed rocker 65 arms 27.

I claim:

1. In a shaking screen, the combination of a plurality of shaker beds, a pair of rock shafts on which said shaker beds are mounted, connections between said rock shafts and 70 said shaker beds affording relative movement between said shaker beds, and means for reciprocating said shaker beds in opposite directions, with means incorporated in said connections for cushioning the shaker 75 beds in their relative movement and for preventing lost motion in the operative parts of the mechanism.

2. In a shaking screen, the combination of a plurality of shaker beds, a pair of rock 80 shafts, connections between said shaker beds and said rock shafts affording relative movement between said shaker beds, and means for reciprocating said shaker beds in opposite directions, with spring cushioning devices incorporated in said connections and adapted to prevent lost motion in the operative parts of the mechanism.

3. In a shaking screen, the combination 90 of a plurality of shaker beds, a pair of rock shafts, rocker arms carried by said rock shafts and connected to said shaker beds, said rocker arms affording relative movement between said shaker beds, and means for reciprocating said shaker beds in opposite directions, with spring cushioning devices 95 associated with said rocker arms and adapted to prevent lost motion in the operative parts of the mechanism.

4. In a shaking screen, the combination 100 of a plurality of shaker beds, supports on which said shaker beds are mounted to rock, connections between said supports and said shaker beds affording relative movement between said shaker beds, and means for reciprocating said shaker beds relatively to each other, with means incorporated in said 105 connections for cushioning the shaker beds in their relative movement and for preventing lost motion in the operative parts of the mechanism.

5. In a shaking screen, the combination 110 of a pair of shaker beds arranged in superimposed relation, supports arranged therebetween, rocker arms associated with said supports and extending upwardly and downwardly therefrom and connected to the shaker beds, and means for reciprocating said shaker beds relatively to each other, with means associated with said rocker arms 115 120 for cushioning the shaker beds in their relative movement to prevent lost motion in the operative parts of the mechanism.

6. In a shaking screen, the combination 125 of a plurality of shaker beds, a pair of rock shafts, oppositely extending rocker arms connected to said rock shafts and arranged in pairs, said rocker arms affording relative movement between said shaker beds, means for reciprocating said shaker beds in oppo- 130

- site directions, a bolt carried by one of the rocker arms of each pair, and a spring carried by said bolt and serving to yieldingly oppose movement of the other rocker arm, 5 whereby to prevent lost motion in the operative parts of the mechanism.
7. In a shaking screen, the combination of a plurality of shaker beds, a pair of rock shafts, rocker arms carried by said rock shafts and connected to said shaker beds, said rocker arms being arranged in pairs, the members of which are reversely disposed and affording relative movement between said shaker beds, means for reciprocating 10 said shaker beds in opposite directions, the rocker arms of each pair carried by one of said rock shafts being provided with perforated overlapping ears, a bolt passing through the ears of each pair, and a spring 15 carried by each of said bolts and interposed between the head thereof and the perforated ear of one of said arms, whereby to yieldingly oppose separation of said arms and prevent lost motion in the operative parts 20 of the mechanism.
8. In a shaking screen, the combination of a pair of shaker beds arranged in superimposed relation, a pair of rock shafts arranged therebetween, rocker arms associated 25 with said rock shafts and extending upwardly and downwardly therefrom, said arms being arranged in pairs and connected to the shaker beds, and means for reciprocating said shaker beds in opposite directions, with spring cushioning devices associated with said rocker arms and adapted 30 to prevent lost motion in the operative parts of the mechanism.
9. In a shaking screen, the combination 35 of a pair of shaker beds, a pair of rock shafts arranged therebetween, rocker arms associated with each of said rock shafts and arranged in pairs thereon, the arms of each pair being reversely disposed with respect 40 to each other and connected to said shaker beds, and means for reciprocating said shaker beds in opposite directions, the rocker arms connected to one of said rock shafts having parallel ears, with resilient 45 devices associated with the ears of each pair and serving to control yieldingly the relative movement of the arms thereof and prevent lost motion in the operative parts of the mechanism.
- 50 10. In a shaking screen, the combination of a pair of shaker beds arranged in superimposed relation, a pair of rock shafts arranged therebetween, downwardly extending rocker arms carried by said rock shafts 55 and connected to the lower shaker bed, upwardly extending rocker arms also carried by the rock shafts and connected to the upper shaker bed, said rocker arms being arranged in pairs the members of which are 60 reversely disposed, and means for recipro- 65 cating said shaker beds in opposite directions, the pairs of rocker arms carried by one of said rock shafts having parallel perforated ears, with a supporting element passing through the ears of each pair and 70 suspended from one of the ears thereof, and a spring carried by said supporting element and contacting with the other ear of the pair, whereby to control yieldingly the relative movement of the shaker arms and prevent lost motion in the operative parts of the mechanism. 75
11. A cushioning mechanism for shaking screens, comprising a pair of rocker arms reversely arranged in relation to each other, 80 a support for said rocker arms, each of said arms having a projecting ear, and cushioning means supported by the ear of one of said arms and cooperating with the ear of the other arm, whereby to control yieldingly the 85 relative movement of said arms.
12. A cushioning mechanism for shaking screens, comprising a pair of rocker arms reversely arranged in relation to each other, a support for said arms, each of said arms 90 having a projecting ear arranged in overlapping relation with respect to the ear of the other arm, a supporting element carried by the ear of one of said arms, and cushioning means supported by said element 95 and cooperating with the ear of the other arm, whereby to control yieldingly the relative movement of said arms.
13. A cushioning mechanism for shaking screens, comprising a pair of rocker arms 100 reversely arranged in relation to each other, a support for said arms, each of said arms having a projecting perforated ear arranged 105 in overlapping relation with respect to the ear of the other arm, a supporting element suspended in the perforated ear of one of said arms and passing through the perforated ear of the other arm, and a cushioning spring carried by said supporting element 110 and acting to control yieldingly the relative movement of said arms.
14. A cushioning mechanism for shaking screens, comprising a pair of rocker arms reversely arranged in relation to each other, a support for said arms, each of said arms 115 having a projecting perforated ear arranged in overlapping relation with respect to the ear of the other arm, a supporting element suspended from one of said perforated ears and passing through the other ear, a coiled 120 spring surrounding said supporting element, the ear through which said supporting element passes being disposed between said spring and the ear from which the supporting element is suspended, whereby said 125 spring cooperates with said ears to control yieldingly the relative movement of said arms.
15. A cushioning mechanism for shaking screens, comprising an upper and a lower 130

4
rocker arm reversely arranged in relation to each other, a support for said arms, each of said arms having a projecting perforated ear arranged in overlapping relation 5 to the ear of the other arm, a supporting element suspended from the ear of the upper arm and passing through the ear of the lower arm, and a spring carried by said suspending element and cooperating with the 10 ear of the lower arm, whereby to control yieldingly the relative movement of said arms.

16. A cushioning mechanism for shaking screens, comprising an upper and a lower 15 rocker arm reversely arranged in relation to each other, a support for said arms, each of said arms having a projecting perforated ear arranged in overlapping relation to the

ear of the other arm, a bolt suspended from the ear of the upper arm and passing 20 through the ear of the the lower arm, a coiled spring arranged beneath the ear of the lower arm and surrounding said bolt, and a washer also carried by the bolt and against which the lower end of said spring 25 is seated, said spring co-operating with the ears of said arms to control yieldingly the relative movement of said arms.

In testimony whereof I hereunto subscribe my name in the presence of two subscribing witnesses.

JOHN C. BUCKBEE.
